UNITED STATES PATENT OFFICE.

EARLE I. STAPLES, OF NEW YORK, N. Y.

PUMPING, FILTERING, AND HEATING SYSTEM FOR OIL-BURNING PLANTS.

Application filed May 5, 1923. Serial No. 637,035.

To all whom it may concern:

Be it known that I, EARLE I. STAPLES, a citizen of the United States, residing at New York city, in the county of New York and

- 5 State of New York, have invented new and useful Improvements in Pumping, Filtering, and Heating Systems for Oil-Burning Plants, of which the following is a specification.
- 10 This invention relates to pumping, filtering and heating systems for oil burning plants and has for its primary object the provision of mechanism of this character including a plurality of pump units arranged
- 15 side by side and superposed with respect to co-acting oil heaters and connected therewith whereby either one or both of said pump units can be used as desired.

Another object of the invention is to provide a system of this character wherein the pump units and co-acting oil heaters are arranged together in a compact manner and adapted to be supported from a floor or similar foundation and thereby reduce the

25 possibility of accidental fires by overhead oil leakage.

Another object of the invention is to provide a system of this character including a supporting structure common to the heaters and said pump units and which will embody a drip tray interposed between said pump units and said heaters so that all drippings from said units will be caught and arrested thereby.

35 A further object of the invention is to provide a system of this character including a heater embodying a steam or heating drum having an oil heating coil formed of a single copper coil whose ends are brought together in close relation and connected to respective external stuffing boxes upon a removable head of said drum, rendering said ends steam tight and providing a structure within the drum which is free of connections which would tend to cause leakage or other trouble in the heating system.

40 Another object of the invention is to provide a system of this character consisting of a plurality of pump units and a corresponding plurality of oil heating units, the latter including companion drums connected with the respective pumps and adapted to be singly or collectively operated therewith and designed and connected with said pump units so that should it be desired to remove

one of the drums for the purpose of repairs, this may be done quickly and without interfering with a successful operation of the other drum and its mating pump unit.

Figure 1 is a side elevation of my improved pumping, filtering, straining and heating mechanism. 60

Figure 2 is a front view thereof.

Figure 3 is a rear view of same.

Figure 4 is a plan view of my improved 65 duplex strainer.

Figure 5 is a section taken approximately on the line 5—5 of Figure 4.

Figure 6 is a section taken approximately 70 on line 6—6 of Figure 4.

Figure 7 is a section on line 7—7 of Figure 6.

Figure 8 is a section on line 8—8 of Figure 6.

Figure 9 is a fragmentary sectional view 75 taken through one of the movable heads of one of the drums and showing the structure of the steam tight coupling joint between the head and the stub end of one of the coils. Figure 10 is a fragmentary view 80 of one of the heads showing a portion of the coupling device referred to in Figure 9.

In carrying the invention into practice, I employ a pair of oil heaters 10, 10, each 85 consisting of a drum having a fixed head 11 and removable head 12. The active oil heating means which I include in the heaters will be referred to in detail hereinafter. These drums are mounted side by side in close relation to each other and same are 90 associated with a frame 13, which includes lower saddle members 14, 14 and superposed mating saddle members 15, 15. The lower saddle members 14, 14 are rigidly connected together by stay rods 16. These frame members are cast so as to allow the drums to be 95 partly embraced thereby and held in a rigid condition. A frame constructed in this manner constitutes a strong and durable foundation for the heaters as well as for the 100 pump mechanism which I will describe presently. The lower members 14, 14 are provided with removable wedge blocks 17 secured to the said members by bolts 18. In this manner, it follows that either of the 105 drums can be quickly and conveniently removed without disturbing the original and intended normal condition of the mating drum. The real advantage of this arrangement will be better understood after refer-

110

ence is had to my twin pumping mechanism which I employ herein as part of my invention.

Mounted upon the frame members 15, 15 5 is a pan 18 and supported thereupon are pumps 19, 19 arranged side by side in vertical alignment with the respective heaters 10 so as to give uniform balance to the entire equipment as will be appreciated. These pumps are connected together 10 by a by-pass 20 having valved connections 21. This by-pass leads from a pipe 22, and the latter is connected with a suction filter 23. Oil may be fed to this filter in the customary manner and taken into the pumps 15 through the valved connections 21 of the by-pass 20. These connections can be controlled manually so that either one of the 20 pumps can be cut off from or arranged in operative communication with the oil supply source as desired. The valves 21 serve to permit both of said pumps to be cut-off from the oil supply source when it is desired to place the mechanism at rest.

25 The pumps are associated with an air chamber 24, and, as shown in Figure 3, this chamber is provided with a pipe 25 having valved branches 26, 26 for operative connection with the oil discharge pipes 27, 27 of said pumps. From this construction, it will be observed that on closing a particular one of said valves 26, the pump leading thereto may be cut-off from the aforesaid pipe 25.

30 In each of the drums 10 is a horizontally disposed coil 28 having a straight branch 29 which extends through the windings of the coil and a stub branch 30, the latter constituting an oil intake to the coil, and the former a hot oil outlet. The intake stub 35 branches are operatively connected with a by-pass 31 having valved ends 32. This by-pass joins with an oil supply pipe 33 which leads from supply pipe 25. In this manner, it will be seen that either one or both of the heating coils 28 can be instantly connected in or disconnected from the supply pipe as desired.

35 The stubs 29^a of the outlet branches are operatively connected with a by-pass 34 having valved ends 35. This by-pass leads to a filter 36 which will be specifically referred to hereinafter.

40 Extending into each of the drums 10 from the head thereof is a long nozzle 37 having 55 valved branches 38 connected with a by-pass 39. This by-pass 39 leads to a pipe 40 which, in turn, is connected with a steam supply pipe 41 which extends from a by-pass 42. The ends of this last named by-pass 42 are 60 provided with valves 43. The pipe 41 is connected with one of these valves 43 and the other of said valves 43 is connected with a pipe 44 which is coupled to a vertical pipe 45, the latter opening to the central portion 65 of a by-pass 46. The by-pass 46 has valved

ends 47 leading to the pumps 19. The vertical pipe 45 is connected with an automatic governor 48, and the latter is joined to a valved air supply pipe 49 leading from the air tank 24. Above and below the governor and mounted in the vertical pipe 45 are steam valves 50, 50. This governor may be of any suitable well-known construction which is adapted to control the speed and pressure of the pump 19. It is preferably of the type shown and described in my co-pending application executed on the 31st day of May, 1923 and filed in the United States Patent Office June 29th, 1923, Serial No. 648,619. Steam from a supply connection 45^a is led to the controlling valve 45^b in aforesaid by-pass 42.

50 The by-pass 34 is provided with the filter 36 as previously set forth and which comprises a body 51 having a tapered rotary plug valve 52 mounted in a seat 53 between the ends of the valve and having its lower restricted end 54 mounted to revolve in a central depression 55 of the body 51. This plug valve is hollow and same is divided by a partition 56 to form an upper chamber 57 and lower chamber 58. Leading to the upper chamber 57 and formed in the walls of the valve plug are ports 59 and 60. The walls of the chamber 50 of the plug are 55 formed to provide ports 61 and 62 and 63 and 64 and as shown, the said ports 63 and 64 are separated from the ports 61 and 62 by a central partition 65.

55 The said body 51 is provided with straining chambers 66 and 67 and suspended from a wall 68 and from above said wall respectively of each chamber are foraminated cylinders or screens 69 and 70. These chambers are disposed in parallel spaced relation to each other and the outer cylinder 70 is spaced from the vertical walls of its respective straining chamber. The said outer cylinder 70 is somewhat shorter than the mating cylinder 69 and same is provided with a flange 71 which rests upon said wall 68. The inner cylinder 69 extends into a space 72 formed in the respective straining chamber and same is closed by a cap 73 which is strapped to the flange 71 by a bail 74. This bail extends over a vertical lug 75 on said cap and associated with said lug is a spring 76. Each space 72 of the respective straining chamber is provided with a threaded cap 77 and bearing against said cap is the upper end of said spring 76. The base of the inner cylinder 69 is provided with a flared member 76^a which is held in sealed contact with a correspondingly flared member 76^b on the lower end of the cylinder 70 by means of said spring 76. By this means, it will be seen that the two cylinders are securely joined together at their lower ends and that the cylinders are firmly held in a relatively rigid condition 115 120 125 130

spaced apart and against chattering when the strainer is in operation. The cap 77 has a diameter in excess of that of the cylinder 70 so that the latter and its mating cylinder can be removed when it is desired to clean these parts. The body 51 is provided with an annular depression 79 which receives a packing 80 and the flange 81 of the respective cap 77. Each of said caps 77 is provided with a small bleed opening 82 so that steam under pressure in the straining chambers can be gradually made to escape from the straining chambers when a particular set of straining cylinders 69 and 70 is removed. By this means, the operator is insured against injury by the action of escaping oil under heavy pressure when removing the aforesaid cylinders.

The body 51 is provided with an oil inlet passage 83 and an outlet passage 84. The inlet passage 83 leads to the upper chamber 57 of the rotary valve 52 and the outlet passage 84 leads to the part of the valve below the partition 56 as shown in Figure 5. When the valve is adjusted to one position the ports 59 and 60 connect the inlet passage 83 with the straining chamber at the left in Figure 8, and the oil as it leaves its heater is conducted to the straining cylinder 69 and 70 of said chamber. In so doing, the oil passes into the space at the top of said chamber below the cap 76 and flows downward through the cylinders 69 and 70 and then through a by-pass 84^a and to the ports 61 and 62 and then to the outlet 84 where it is conducted to the burners, (not shown). The same operation is true of the filtering chamber to the right when the valve plug is adjusted to its second position. In this manner, it being understood that the inlet passage 83 is connected with the by-pass 34, it follows that oil may be passed in a continuous manner to the filter and that the cylinders 69 and 70 of a respective filtering chamber can be removed and cleaned without causing any interruption to the filtering process as the hot oil is pumped from the heaters.

The pump valve 52 is provided with a stem 85 having portions 86 and 87 of graduated diameters. These portions are journaled to rotate in a removable cap 88 carried by the body 51. A spring 89 between the plug and the shoulder 90 of said cap serves to yieldingly hold the plug in its seat. The cap 88 carries a suitable stuffing gland 91. The cap is provided with an annular flange 92 which co-acts with a groove 93 in the valve body, and between this flange and the walls of the groove is a packing gasket 94. The gland 91 includes a metallic washer 91^a which bears against the shoulder 91^b at the junction of the portions 86 and 87. Should the spring 88 break while the structure is

in use it will be observed that motion in an upward direction of the plug is prevented and that no leakage occurs as a result of such breakage.

The plug carries a fixed handle 95 having a lug 96 adapted to co-act with stops 97 and 98 on the valve body. These stops are related to the filtering chambers so that when the valve is adjusted to one position, one chamber is cut off from the oil supply source and the other connected directly therein. Each filtering chamber has moulded or otherwise formed thereon the word "Off" and the handle has formed thereon in a similar manner, the word "On". The width of the handle of the valve is such that the word "Off" of one filtering chamber is always covered by the handle and the word "On" of the handle exposed as shown in Figure 4. This enables the operator to quickly understand which of the filtering chambers is in active service.

The stub ends of each heating coil are welded at 99 in the reduced sockets 99^a of coupling devices 100. These devices are each formed with a squared head 101 fitting in a correspondingly formed collar 101^a on the removable head of the oil heating drum. The head 101 is provided with a reduced cylindrical end 102 fitting in a passage 102^a in the drum head and extending from this end 102 is a threaded nipple 103 which joins its pipe connection. In other words one of these devices connects the intake end of the oil heating coil with the pipe 33 and the other of said devices connects the outlet of the coil with the strainer 36. The nipple 103 is provided with a clamping nut 104 which co-acts with a gland 105 to clamp the head 101 in the collar 101^a. In this manner, it will be observed that steam tight joints are formed between the coil stubs and the head of the mating drum and that the coil is secured against accidental derangement due to the action of expansion and contraction.

Each of the straining chambers 63 and 67 is provided with a drain cock 106. The outlet of the chamber is disposed above the base of the latter so that each chamber constitutes a sediment trap at a point below said outlet.

Each of the heating drums 10 is provided with a valved drain connection 107.

Having described the invention in detail its operation is set forth as follows:

It is assumed that both pumps 19 are operating; that the valves in the steam connections from the pumps are open so as to admit steam to said drums at points within the windings of the oil heating coils 28 and that oil is being introduced to the coils to be subjected to the action of the steam. In this manner a continuous flow of oil is conducted through the coils of the aforesaid

heaters and as the hot oil emerges from said heaters it is taken into the strainer mechanism 36 and finally led therefrom, to the burners of a heating plant. As stated elsewhere herein either of the chambers 66 or 67 can be used in conjunction with the pumps singly or collectively. As the oil enters the intake passage 83 of the strainer mechanism 36 it is by-passed by way of the ports 59 and 60 to the respective filtering chamber. It is then conducted in a downward direction through the strainer cylinders 69 and 70 and then taken off from the chamber through the lower ported structure 15 of the rotary valve 52. As the oil takes this course it is subjected to an extremely effective filtering process and all sand and sediment is held against passing to the burners. By providing the cylinders 69 and 70 with 20 the joints 76^a and 76^b at their lower ends, the cylinders constitute a trap for sediment and at a requisite time both cylinders can be conveniently removed and subjected to a cleaning process. As stated, the base of 25 each filtering chamber also constitutes a sediment trap and through the characterizing features of the filtering mechanism these chambers can be placed under individual control whenever it is desired to relieve 30 same of their accumulated sediment.

The pipe 40 has a steam pipe 108 leading therefrom and connected by a valve 109 to the suction filter 23 from which oil is fed to the pumps. This suction filter 23 is provided with a drain valve 110. By means of 35 this arrangement it will be observed that steam from the pipe 40 can be made to enter the said filter to render the same self cleaning.

40 The filter 36 is so constructed that the combined area of the cylinders 69 and 70 thereof is approximately ten times greater than the area of the intake opening of the filter 36 so as to give ample straining 45 surface and to operatively permit an unrestricted flow of heated oil from the system. In operation of this strainer, oil enters the top of each chamber and part of the oil flows down into the space between the respective cylinders 69 and 70 thence through 50 the perforations in the cylinder 70 directly to the outlet of the strainer, while other oil passes through the upper extended end of the cylinder 69 thence in a downward direction therethrough until it reaches the base of the filtering chamber. It then 55 passes up to the outlet of the strainer as shown by the arrows. This provides for free circulation of the oil and causes any 60 heavy sediment to respectively lodge in the

space between the cylinders 69 and 70 and upon the bottom of the filtering chamber.

What is claimed as new is:—

1. An oil heating, pumping and filtering system comprising a pair of oil heaters, 65 frames supporting said heaters in parallel relation to each other, a pan supported by said frames above said heaters, pumps rising from the pan and disposed in vertical alignment with the respective heaters, a horizontally disposed coil arranged in each heater and coiled from its inlet and having a straight portion extending to its outlet, means for causing filtered oil to be delivered to the pumps and then discharged to said 70 coils and a filter connected with said coils to receive the heated oil therefrom and for causing said oil as it leaves the filter to pass to the burner line of a heating plant, means for delivering steam to the central portion of 75 said heaters to serve as a heating agent for the oil flowing through said coils.

2. Mechanism of the class described comprising a plurality of identical oil heaters, 80 a pump for each heater, a valved connection 85 between each pump and its respective heater, means for causing filtered oil to be conducted to the pumps and discharged therefrom to said valved connections, whereby to cause oil under pressure to be delivered to the heaters, 90 means for subjecting the heaters to the action of a heating agent, a strainer common to all of said heaters, and valved means between each heater and said strainer for causing one or all of said heaters to be arranged 95 in operative connection with said filter, a pan superposed with respect to all of said heaters and constituting a support for all of said pumps, and a frame rigidly joining the heaters of the pan.

100 3. Mechanism of the class described comprising a plurality of oil heaters, an individual pump for each heater, means for causing oil to flow to the pumps and to pass therefrom to the respective heaters, means 105 serving as a source of reception for oil flowing from one or all of said heaters, and including valved connections receiving heated oil from the heaters, and a frame structure superposing the pumps with respect to the heaters and including saddles arranged respectively above and below the heaters and serving to permit of sidewise withdrawal of one of the heaters from the frame without disturbing the normal relation of the other 110 115 of said heaters.

In testimony whereof I have affixed my signature.

EARLE I. STAPLES.
